KITCHEN FAUCET HANDLE

James Edward Niemann, Louisville, Ky., assignor to
American Standard, Inc., New York, N.Y.

Continuation-in-part of design application Ser. No. 20,160,
Nov. 18, 1969. This application Nov. 2, 1970, Ser.
No. 25,974

Term of patent 14 years

Int. Cl. D23—01

U.S. Cl. D23—29

FIG. 4

FIG. 2

FIG. 3

FIG. 1

FIG. 1 is a side elevational view of a kitchen faucet handle embodying my new design;

FIG. 2 is a top plan view thereof;

FIG. 3 is a front elevational view thereof; and

FIG. 4 is a perspective view thereof.

This is a continuation-in-part of design Application Ser. No. D. 20,160, filed Nov. 18, 1969, now Design Pat. No. D. 21,939.

I claim:

The ornamental design for a kitchen faucet handle, substantially as shown.
